UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,789, dated September 19, 1893.

Application filed August 16, 1893. Serial No. 483,416. Term of patent 3½ years.

To all whom it may concern:

Be it known that I, CHARLES BOOZE, a citizen of the United States, residing at the city of Buffalo, in the county of Erie and State of New York, have invented a new and original Design for Wall-Paper, of which the following is a specification.

This design consists of ornamental vase-like forms filled with flowers and leaves as represented in the accompanying drawing. From each side of said vase-like forms and connected to the same are ornamental scrolls composed of flowers and leaves and ornamental scrolls.

The design is printed in any desired color or colors or in bronze and is intended for a wall decoration.

What I claim is—

The design for wall paper herein shown and described.

Witness my hand this 7th day of August, 1893.

CHARLES BOOZE.
